UNITED STATES PATENT OFFICE.

HAROLD N. ANDERSON, OF CLEVELAND, OHIO.

APPARATUS FOR ROLLING GEARS BY A NEW METHOD.

Application filed September 17, 1920. Serial No. 410,866.

To all whom it may concern:

Be it known that I, HAROLD N. ANDERSON, a citizen of the United States, residing at Cleveland, in the county of Cuyahoga and State of Ohio, have invented new and useful Apparatus for Rolling Gears by a New Method, of which the following is a full, clear, and exact description.

My present invention relates to apparatus for rolling teeth on gears by a new method.

In United States Patent No. 1,001,799 I showed a machine for rolling spur gears, using first a toothed breaking-down roll and then a toothed finishing roll for forming teeth on a heated gear blank. While it was intended that this machine should operate continuously in one direction I suggested that in order to effect certain results the direction of rotation might be reversed at some point in the operation. In United States Patent No. 1,240,915 I showed a machine for rolling spur gears with a single toothed die roll, this machine also being intended to operate in one direction. In United States Patents Nos. 1,240,914; 1,240,916; 1,240,917 and 1,240,918 I showed machines for rolling bevel gears with die-rolls rotating in one direction. In United States Patent No. 1,240,913 I showed a machine for rolling spur gears with a reciprocating rack, which, of course, necessitated oscillatory motion of the blank. In these machines teeth were formed on the blank by pressing the die and rotating blank together, gradually sinking the die teeth into the blank to the required depth, forming the teeth by what is known as the generating principle.

My present invention consists in forming teeth on the blank by oscillatory rotation followed by continuous rotation of the blank in one direction. The die teeth are sunk to nearly, if not quite the full depth in the blank during the oscillatory rotation, so that the principal effect of the subsequent rolling in one direction is to smooth and planish the surfaces of the teeth. I prefer to rotate the blank at moderate velocity during the oscillatory stage of the operation and increase the velocity considerably during the continuous rotation. By "moderate velocity" I mean a velocity such as is most practical under given conditions; that is, in view

of the size of the blank, the weight of the oscillatory parts, etc.

In United States Patent No. 1,237,125 I explained the action of the die teeth as they enter and leave the blank, and pointed out that because the die teeth move toward the axis of the blank on entering and away from the axis on leaving the spaces between the teeth, there is a slight though negligible difference in the effect produced on the two sides of the spaces. As was there stated this difference is neutralized in the machine disclosed in Patent No. 1,240,913, where the teeth are generated with a reciprocating rack. The principal object of the present invention is to provide means for employing this reciprocatory method in connection with a rotary die, and adapt it to rolling bevel and other types of gears as well as spur gears.

Another object is to combine the desirable features of both methods of rolling in a single machine. By forming the teeth with oscillatory motion they are the same on both sides and they have a uniform texture; that is, the fibrous structure of the teeth, which has a form somewhat like that of the teeth, is made symmetrical. On the other hand, the subsequent rolling in one direction, and preferably at a considerably increased velocity, gives the tooth surfaces a fine smooth finish. If the oscillatory rolling is succeeded by direct rolling before the die has been sunk to the maximum depth in the blank the metal composing the teeth is made very dense and tough and the surfaces of the teeth are freed from scale and planished. The effect of any backlash that may be present in the timing mechanism or elsewhere is also removed and the teeth brought to the correct thickness.

In the accompanying drawings I have shown two embodiments of my invention, adapted to roll bevel gears and one for rolling spur gears.

Fig. 1 is a plan view of one of the machines for rolling bevel gears.

Fig. 2 is a rear elevation of a portion of the machine shown in Fig. 1, it being the mechanism by which the die and blank are oscillated.

Fig. 3 is an elevation, principally in section, of the mechanism for rectifying the direction of rotation of the cam by which the die roll is moved toward the blank.

Fig. 4 is a transverse section of the mechanism shown in Fig. 3, taken on line 4—4.

Fig. 5 is a front elevational view of a portion of the manually controlled clutch shifting mechanism.

Fig. 6 is a side elevational view of the mechanism seen in Fig. 5.

Fig. 7 is a view of the cam by which the die is pressed into the blank.

10 Fig. 8 is a detail showing an improved blank supporting mechanism.

Fig. 9 is a plan view of the other machine for rolling bevel gears. In this machine the oscillatory motion is produced with a 15 crank and toothed segment.

Fig. 9^a is an elevational view of the crank and sector for oscillating the die roll and blank.

20 Fig. 10 is a plan view of the machine for rolling spur gears.

Referring now to Fig. 1, the gear rolling portion of the machine is mounted on a base 25, while the driving mechanism is mounted on a base 26, the two bases being united at 25 27. A shaft 28 is mounted to rotate in bearings 29 and 30 carried by the base 25. At one of its ends this shaft carries a timing gear 31. A superbase 32 is mounted on the base 25 and arranged to be swung to various 30 positions on the base around an axis shown in dotted lines at 33. It is secured in any desired position on the base 25 by means of bolts 34 whose heads are located in T slots 35 formed in the base 25. The superbase 35 carries bearings 36 and 37, in which is journaled a shaft 38. One end of this shaft carries a beveled timing gear 39, which gear is in mesh with the timing gear 31. The shaft 38 also carries a holder for supporting bevel gear blanks while teeth are being 40 rolled on them, a portion of this holder being seen at 40.

The shaft 28 is tubular and within it there is a shaft 45. This shaft is adapted to slide 45 endwise in the shaft 28, but is attached to the shaft 28 by splines (not shown) that cause the shafts 28 and 45 to rotate as though they were one. Adjacent to one end of the shaft 45 is a follower 46 arranged to 50 slide in guides 47 carried by the base 25, and the shaft 45 and follower 46 are connected together by a suitable thrust bearing 48 which compels the shaft and follower to move as a unit, but allows the shaft to 55 rotate with reference to the follower. A collar 49 is clamped on the shaft 48 and a similar collar 50 on the end of shaft 28. Between these collars a compression spring 51 is confined, which spring tends constantly 60 to move the shaft 45 endwise in the shaft 28 in the direction that will carry the shaft 45 away from the blank holder 40. A roller 52 is mounted to rotate on the follower 46; the function of this roller will be described 65 later. On the end of shaft 45, adjacent to

the blank holder 40 is mounted a die roll (not shown) adapted to generate teeth on a heated blank carried by the holder.

The preceding two paragraphs describe the elements of a machine for rolling bevel 70 gears which is not essentially different from the corresponding parts shown in my Patent No. 1,240,916. It is therefore deemed unnecessary to go into further details concerning this part of the machine, as my present invention relates more particularly to the mechanism for driving the parts just described than to the structure of the parts themselves. I will now describe the mechanism for imparting oscillatory rotation to 75 the parts already described:

A jack shaft 60 is mounted in bearings 61 carried by the base 25, and a bearing 62 carried by base 26, this shaft being connected to shaft 28 by bevel gears 63 and 64; the latter being keyed to shaft 28. The jack shaft carries a bevel gear 65 which is enmeshed with two bevel gears, 66 and 67, mounted to rotate freely on a shaft 68, these gears being on opposite sides of gear 65. 80 This shaft is rotated constantly through a worm gear 69 by a motor 70, the motor shaft 71 and worm shaft (not shown) constituting what will presently be referred to as the main shaft. Gears 66 and 67 are 85 coupled alternately to the shaft 68 by means of clutches 72 and 73, the clutches being operated by a shifting mechanism that will be described presently. It is evident that since the shaft 68 rotates constantly in one direction, the shaft 60 will be rotated in one direction by the clutch 72 and gear 66, and rotated in the opposite direction by the clutch 73 and gear 67.

For the purpose of rotating the jack shaft 60 continuously in one direction I provide a pulley 74 loosely mounted on the jack shaft, which is driven by a belt 75 and pulley 76, carried by the motor shaft. While a simple belt is here shown, it is to be understood that this drive may be through the medium of sprockets and a chain. The pulley 74 is connected to the jack shaft when desired by a clutch 77.

The mechanism for operating the clutches 72 and 73 will now be described and in this connection reference will be had to Figs. 1 and 2. A shaft, 80, mounted in bearings 81 carried by the base 26, is constantly rotated through a belt or chain 82 by the shaft 68. Two cams, 83 and 84, are mounted on the shaft 80 and while adapted to slide endwise on the shaft they are compelled to rotate in unison therewith by splines (not shown). The cams are connected through the medium of sleeves 85 to collars 86, these collars, in turn, being connected to a fork 87 by means of links 88. The connection between the sleeves 85 and collars 86 is such as permits the sleeves to rotate in the col- 115 120 125 130

lars while the latter remain stationary. The connection between the fork 87 and links 88 is effected by means of studs 89 fixed in the tines of the fork 87. These studs extend beyond the hubs of the links and into stationary guides 90. The fork 87 is fixed to the and of a rod 91 shown in dotted lines in Fig. 1, the other end of the rod being pivotally attached to an arm 92 keyed to the lower end of a vertical shaft 93 (see Figs. 5 and 6). The links 88 constitute a toggle joint of which the fork 87 is the knuckle, and when the fork is moved to a position where the axes of the studs 89 intersect the axis of shaft 80; in other words, when the links 88 are moved to a position where they are in alignment with each other, the cams 83 and 84 are moved on the shaft 80 into operative positions. They occupy this position in Fig. 2.

When the fork 87 is moved by the rod 91 and lever 92 to the position shown in Fig. 1, cams 83 and 84 are drawn toward each other by the links 88 and out of operative positions. The clutches 72 and 73 are provided with the usual shifting collars 100, each of which is moved longitudinally on the shaft 68 by a shifting lever 101, these levers being mounted to rock on fixed centers 102. Each of the levers carries a roller 103 that cooperates with one of the cams, 83 and 84. The levers 101 are connected together by a rod 104 so that they move in unison.

Referring now to Fig. 2 it will be seen that the cam 84 has rocked its lever 101 in the direction necessary to close the clutch 72; the gear 66 is therefore driving the gear 65 while the gear 67 is being driven idly by the gear 65 in a direction opposite to that in which the shaft 68 rotates, this being possible because the clutch 73 is open. When the shaft 68 has rotated a predetermined distance, it being recalled that the shaft 80 is constantly rotated by the shaft 68 through chain 82, the cam 83 will shift the lever 101 and close clutch 73. Simultaneously the clutch 72 is opened by the rod 104 that connects the levers 101, the cam 84 having rotated to a point where it will permit the movement of the lever. The gear 67 will now be in driving connection with the shaft 68 and capable of rotating the gear 65. But since the gear 67 meshes with the side of gear 65 opposite to that with which gear 66 meshes, it is seen that the gear 67 rotates the gear 65 in a direction opposite to that in which gear 66 drives it. When the shaft 68 has rotated a predetermined distance with the clutch 73 closed, the cam 84 again closes clutch 72, clutch 73 being simultaneously opened, and the direction of rotation of gear 65 is again reversed. In this way the gear 65 is driven automatically a predetermined distance in each direction, the reversals being effected automatically as long as the cams 83 and 84 remain in operative position.

When the oscillatory motion has continued the desired length of time the shaft 93 is rocked, and through the medium of arm 92 and rod 91 the fork 87 is moved to the position shown in Fig. 1, thereby moving the cams 83 and 84 to their inoperative position. The sleeves 85 extend beyond the cams 83 and 84 and at their ends carry disks 94. Moving the links 88 to the position they occupy in Fig. 1, carries the sleeves toward each other sufficiently so that the disk 94 will engage the lever 101 whose clutch happens to be closed and rocks the lever far enough to open the clutch.

The mechanism for starting, stopping and controlling the machine will now be described: The vertical shaft 93 is mounted to rock in a bracket 110 carried by the base 26. An arm 111 is keyed to the upper end of the shaft and it is provided with a recess 112 formed by two depending lugs 113. A short distance below the hub of the arm 111 a similar arm, 114, is loosely mounted on the shaft 93, the outer end of this arm having a recess 115 similar to recess 112 and also formed by lugs 116, these lugs, however, extend upward instead of depending. Secured to the hub of the arm 114 is a sleeve 116 which extends downward on the shaft 93 a suitable distance and at its lower end carries a forked arm 117. Loosely mounted on the shaft 93 between the hubs of the arms 111 and 114 is a collar 118 to which is pivotally attached a lever 119, the pivotal axis 120 being horizontal, so that the lever may be rocked upward or downward from a central or neutral position. The lever may also be laterally rocked because of the collar being loosely mounted on the shaft. Each of the arms, 111 and 114, carries a flat spring 121. These springs bear against opposite sides of the lever 119 and hold it in a central or neutral position. The forked arm 117 is connected to the clutch 77, so that when the arm 114 is rocked on the shaft 93 the clutch is opened or closed.

By referring to Figs. 5 and 6 it will be seen that the recesses 112 and 115 are opposite each other and that by rocking the lever 119 upward on its axis 120 the lever may be made to engage in recess 112. By rocking it downward it will engage in recess 115. With the arms in the positions shown in these views all of the clutches are open. To close the clutch 77 the lever is first rocked downward into the recess 115 and then swung to the left. To throw the oscillatory mechanism into operation the lever would be raised into the recess 112 and then thrown to the left, the lever is thus coupled at will to either arm. To prevent the lever from being disengaged from either arm before the arm has been returned to its home position I provide a stationary

locking bar 122 which is mounted on an extension 123 of the bracket 110. When the lever 119 is engaged with one of the arms and thrown to the left, the locking bar 122 prevents its disengagement from the arm without first being returned to the normal or home position. By this means closing the clutch 77 while the oscillatory mechanism is in operation, or throwing in 10 the oscillatory operation while the clutch 77 is closed is prevented.

I will now describe the mechanism for moving the shaft 45 longitudinally and pressing the teeth of the die roll into the heated blank in the holder 40. A shaft 130, rotating in bearings 131 on the base 25, has keyed to it a cam 132 and it is necessary to rotate this cam one revolution to roll each blank, moving it continuously in one 15 direction, notwithstanding the other parts of the machine are oscillating part of the time. A worm gear 133 is keyed to the shaft 130 and is driven by a worm (not shown) on the shaft 134, which rotates in bearings 135. A shaft 136 in longitudinal alignment with shaft 134 rotates in bearings 137 and is driven by spiral gears 138 and 139. When the jack shaft is being driven by the clutch 77 the shaft 136 drives shaft 134 through an automatic friction clutch (see Figs. 3 and 4). This will now be described.

In Fig. 3 it will be seen that the ends of the shafts 134 and 136 almost abut. Keyed to the extreme end of the shaft 136 is a gear 140 having a hub 141 to which is keyed the member 142 of the automatic friction clutch, this being seen to the best advantage in Fig. 4. Keyed to the extreme 35 end of the shaft 134 is a gear 143 having a hub 144. Secured to this hub is a ring 145 which extends beyond the hub into the zone of the member 142. The member 142 is cut away at three points to form recesses 146 in which rolls 147 are confined. The faces 148 thus formed upon the member 142 are slightly eccentric and when the member 142 rotates in the direction indicated by the arrow in Fig. 4 there is a tendency for the rolls to roll to higher points on the faces 148, which causes the rolls to become jammed between the faces 148 and the interior of the ring 145 and enables the member 142 to drive the ring 145. When the member 142 rotates in the opposite direction to that shown by the arrow the rolls tend to roll to lower points on the eccentric faces and thus relieve the pressure against the ring 145 and allow the member 142 to rotate freely within the ring. The rolls are constantly pressed toward the higher points of the eccentric faces by spring-pressed plungers 149, so that when the member 142 starts to rotate in the direction indicated by the arrow the rolls grip the ring

145 almost instantly, so that there is substantially no lost motion in that direction by the member 142.

During the oscillatory operation of the machine the shaft 136 is oscillated along 70 with the other parts of the machine. Half of the time, therefore, it is rotating in a direction opposite to that in which the clutch 77 drives it and at these times the member 142 rotates in the direction opposite to that 75 indicated by the arrow in Fig. 4. For the purpose of driving the shaft 134 at these times I provide a rectifying device, comprising a second automatic clutch mounted on a shaft 150. A gear 151 keyed to this shaft is driven by the gear 140 through an intermediate gear 152, shown also in dotted lines in Fig. 4. Keyed to a hub forming part of this gear 151 is a clutch member 153, just like member 142 except that the eccentric faces face the opposite way. Loosely mounted on the shaft 150 is a gear 154 carrying a ring 155 similar to ring 145. Rolls 156 confined in the recesses perform the same function as rolls 147. When the 80 shaft 136 rotates backward, that is, contrary to the direction in which clutch 77 drives it, the gear 154 is frictionally driven by this second clutch and it drives the gear 143 in the same direction that the member 142 85 drives it. It is thus seen that whether the machine is oscillating or rotating continuously in one direction the shaft 134 is rotated forward, driving the cam 132 in the 90 right direction always.

Fig. 7 is an enlarged view of the cam 132 and in dotted lines a portion of the roller 52 is shown in the position it occupies with reference to the cam when a gear blank is being placed in the holder 40. The follower 46 is constantly urged by the spring to move toward the cam, so that the roller 52 bears on the periphery of the cam at all times. When the blank has been secured in the holder the operator raises the lever 119 and throws it to the left, thus putting into operation the oscillating mechanism, which causes rotation of the cam in the direction indicated by arrows in Figs. 1 and 7. For purposes of explanation the cam is assumed to be divided into several sectors; the action of the sector A—B is to move the roller 52 a considerable distance toward the blank, which brings the die roll practically into engagement with the blank. The sector B—C continues the movement of the die and causes the teeth to sink into the blank, the die and blank continuing to oscillate during this time. I prefer to time the oscillation so that the blank will rotate approximately from one to three revolutions each way. This however is not essential and in some cases different timing may be found preferable. The timing may be varied by changing the speed ratio of shafts 100 105 110 115 120 125 130

68 and 80. There are other ways of doing this of course, which any skilled mechanic would easily see. At about the time the point C on the cam reaches the roller 52, the operator will return the lever 119 to its central position, thereby stopping the oscillation of the machine, and he will then move the lever downward, thus coupling it to the arm 114, and throwing it to the left 10 will close the clutch 77 and start the machine to rotating in one direction. As the oscillating mechanism is driven through the worm gear 69 it is seen that the velocity at which the die and blank oscillate is much 15 less than when they are being rotated by the clutch 77, for at that time the jack shaft is driven by the belt 75 directly from the main or motor shaft 71. The sector B—C of the cam 132 sinks the die teeth nearly, 20 but not quite to the final depth in the blank; the completion of the die's advance into the blank is effected by the sector C—D. This slight additional advance into the blank, accompanied as it is by rapid rotation 25 in one direction compacts the metal of the teeth and gives them the final and correct form. The sector D—E simply holds the die at the final depth in the blank while the rapid rotation continues, which serves to planish the teeth and remove any forging scale that may remain on them. While the roller 52 is traversing the sector E—A the operator opens the 30 clutch 77 by returning the lever 119 to its home position and stops the machine at the required point by operating the handle 160 of a band brake 161 which surrounds the shaft 28 adjacent to the timing gear 31. As the cam mechanism is driven by the jack 40 shaft 61, which also drives the die and blank holder, the velocity of the cam varies just as the velocity of the die and blank holder varies. It is seen, therefore, that while the 45 characteristics of the movement of approach between the die and holder are determined by the contour of the cam, the movement of approach is modified in accordance with the velocity of the die and holder.

Instead of leaving a portion of the die's 50 advance into the blank to be effected after continuous rotation in one direction has begun, the advance may be completed during the oscillatory operation. Furthermore, the continuous rotation may be omitted and 55 the blank completed by oscillation alone. Obviously, these steps are within the scope of my invention, but I prefer the procedure first described: by sinking the die to nearly the required depth by oscillatory rotation a 60 symmetrical tooth structure is built up which will be practically unaffected by the slight additional advance which the die makes during the one direction rotation. The one direction rotation may be regarded 65 as merely a prolongation of the last step in

the oscillation, and if desired the advance of the die into the blank during this last step need be no greater than its advance during any single step of the oscillation. I mention these things to show the flexibility of my new 70 method and how the advantages of one way rotation and oscillatory rolling may be combined, so that the product embodies the desirable characteristics imparted by each.

It occasionally happens that a blank must 75 be returned to the holder and rerolled. In such cases it is important to place the blank in the holder in a position where the die teeth will enter between the teeth which have been more or less completely formed on the blank. For this purpose I provide a lever 165 pivoted at 166, having an upwardly extending member 167 adapted to engage a lug 168 extending laterally from the follower 46. Ordinarily, the lever rests 80 on a stop pin 169 and when it is necessary to use the lever this pin is removed, so that the lever may be rocked downward, bringing the member 167 into engagement with the lug 168. Continued downward motion of the lever moves the shaft 45 and therefore the die toward the blank. The operator turns the blank in the holder to a position where the die teeth enter properly between the teeth of the blank and while pressing the die gently against the blank and the blank into the holder by means of the lever 165 he 85 clamps the blank in the holder; then when the blank is rerolled there is the minimum of disturbance of the teeth that were formed 90 during the previous rolling.

Fig. 10 shows a modification of the machine which has just been described, adapted 95 to roll spur gears, and as the mechanism for oscillating the die and roll and subsequently rotating them in one direction only is identically the same as that just described, it is not necessary to again describe it. The same reference numerals are affixed to the several parts as were used in describing the corresponding parts in the previously described machine. I will therefore confine the 100 description of the spur machine to the parts that are different.

Referring now to Fig. 10, the jack shaft 115 60 carries a spur gear 175 in place of the bevel gear 63 carried by this shaft in Fig. 1. This gear meshes with a gear 176 on a shaft 177 that is journaled in bearings 178. The shaft 177 carries one member 179 of the blank holder. The opposite member, 180, of the blank holder is carried by one end of a shaft 181 which is adapted to slide longitudinally and rotate in a bearing 182. The shaft 181 is moved toward the shaft 177 by 120 a spring (not shown) and it may be moved in the opposite direction by means of the lever 183 fulcrumed at 184. When the blank 185 is inserted between the members 179 and 180 of the holder it is clamped temporarily 125 130

by the spring before referred to, which moves the shaft 181 toward the shaft 177. Die roll 186 is mounted on a shaft 187 journaled in bearings 188 that are carried by 5 sliding carriage 189, this carriage being supported by guides 190 carried by the base 25. The shaft 187 is driven by the jack shaft 60 through universal joints 191, which allows the die roll 186 to be moved to and fro with 10 reference to the blank while the proper speed ratio of the die and blank is maintained by the gears 175 and 176.

On the end of the shaft 181 remote from the blank is attached a thrust bearing 192 which carries a ramp 193. Projecting laterally from the carriage 189 is an arm 194 carrying a block 195 whose position may be adjusted with reference to the arm 194 by a screw 196. When the carriage 189 is moved 20 to bring the die roll into engagement with the blank the block 195 rides across the ramp 193 and presses the blank holder member 180 firmly against the blank. The blank is thus held tightly in the holder while the 25 die operates on it and is automatically released as the die is withdrawn, so that all the operator needs to do to remove the blank is to move the shaft 181 by means of the lever 183 in opposition to the spring previously referred to. The parts so far described are substantially the same as corresponding parts in my Patent No. 1,240,915, so a more detailed description of these parts is unnecessary here.

30 The present machine has a shaft 45 which is moved endwise in one direction by a spring 51 and in the other direction by the cam 132 just as is the case in the machine shown in Fig. 1. The shaft 45 is attached 40 to the carriage 189 and moves the carriage to and fro just as in the other machine it moves the die roll. Instead of carrying the worm for driving the wheel 133, shaft 184 carries a gear 200 which meshes with gear 45 201 secured to a shaft 202 mounted in a bearing 203, which shaft carries the worm (not shown) that drives the gear 133. With this exception, the die is advanced by motion of the jack shaft 60 with either oscillatory or direct rotation, just as in the machine shown in Fig. 1. The purpose of interposing the gears 200 and 201 is to enable the ratio of movement between shafts 60 and 130 to be varied if desired. It is apparent 50 that this same change gear arrangement can be incorporated in the machine shown in Fig. 1, if desired. The operation of this machine is the same as has been previously described, and it is evident that the same 55 advantages are obtained here in connection with spur gears as has been described with reference to bevel gears made in the machine of Fig. 1.

In Fig. 9 I show a machine for rolling 60 bevel gears which operates on a different

principle from either of the machines already described. In this machine the blank 210 is carried on the end of a jack shaft 211 mounted in bearings 212. A bevel gear 213, loosely mounted on the jack shaft, 70 is enmeshed with a bevel gear 214 carried on a worm shaft 215 (see Fig. 9A), which is connected to the shaft of the motor 216. By means of a clutch 217 the gear 213 is put into driving connection with the shaft 211 75 and the shaft is thus driven in one direction by the motor. For the purpose of oscillating the shaft 211 I provide a worm gear 220 that is driven by a worm on the shaft 215. The worm gear is mounted on a shaft 221 80 which carries a crank 222 that is connected by a pitman 223 to a toothed segment 224, arranged to rock on an axis 225. The segment meshes with a pinion 226 that is loosely mounted on the shaft 211 but which, when 85 desired, is put into driving connection with the shaft by a clutch 227. The clutches 217 and 227 are operated selectively, one being opened and the other closed, and vice versa, by a lever 228 fulcrumed at 229. This lever 90 operates the clutch 217 directly and the clutch 227 by means of a link 229 and a lever 230 fulcrumed at 231. The segment 224 rocks constantly whenever the motor is running and by shifting the lever 228 in one 95 direction the clutch 227 is closed and the jack shaft oscillated, while shifting it in the opposite direction closes the clutch 217 and causes the jack shaft to be driven constantly in one direction.

100 A timing gear 235 is keyed to the jack shaft 211 and meshes with a timing gear 236, rigidly fixed to a shaft 237 mounted to rotate in bearings carried by a superbase 238. The shaft 237 is tubular and contains a shaft 239 105 which is connected to shaft 237 by a spline that makes the shafts rotate as a unit but allows the inner one to move longitudinally. A die roll 240, carried by the end of shaft 239, may be pressed against the blank by 110 moving the shaft 239 endwise. The shaft 239 is connected to a follower 241 by a thrust bearing 242 and the follower carries a roller 243 that is acted upon by a cam 244 similar to the cam 132 previously described. The cam 115 is carried on a shaft 245 that is driven by a shaft 246 through a spiral gear 247. The shaft 246 carries a gear 248 which meshes with a gear 249 carried by a shaft 250, mounted in a bearing 251. The shaft 250 is 120 driven through a telescopic shaft 252 and two universal joints 253 by a shaft 254 mounted to rotate in bearings 255. Loosely mounted on shaft 254 are two bevel gears, 256 and 257, both of which are enmeshed 125 with a bevel gear 258 fixed to the worm gear shaft 221. Each of the gears, 256 and 257, carries a clutch member which is adapted to cooperate with a clutch member 259 splined on the shaft 254. The member 259 may be 130

shifted by a lever 260 to engage either gear 256 or 257, or to a central position where it engages neither of them. It is seen that the cam 244 will be rotated in one direction or 5 the other according to which of the bevel gears, 256 or 257, the clutch member 159 is engaged with. The shaft 239 is constantly urged toward the cam 244 by a compression spring 261. At the time a blank is being 10 placed in the holder the die roll is fully withdrawn, the roller 243 occupying a position with reference to the cam 244 the same as roller 52 occupies with reference to the cam 232 in Fig. 7. When the blank is in 15 place the operator closes the clutch 227 which starts the machine to oscillating; and he also shifts the lever 260 to start the die advancing mechanism. For this purpose he shifts it in the direction which will cause the 20 cam 244 to be rotated in the direction indicated by the arrow on the cam. At the proper time he opens the clutch 227 and closes the clutch 217 and finishes rolling the blank at high speed in one direction. 25 Most of the time the clutch member 259 will be engaged with the same gear (256 or 257) and the only time that it will be necessary to reverse the direction of the die advancing mechanism is in case of something unusual 30 happening; such as the machine becoming jammed or if for any reason the operator wishes to relieve the pressure temporarily. This is a feature which may very readily be applied to either of the machines previously described.

While the machine just described is adapted to roll bevel gears having any number of teeth it is especially adapted to roll pinions having comparatively few teeth. In 40 Fig. 9 it is shown set to roll pinions with very few teeth. To arrange it for rolling pinions with more teeth it is only necessary to swing the superbase 238 around on the axis 265. As the superbase is swung around, 45 the telescopic shaft 252 and universal joints 253 automatically accommodate themselves to the changed angularity of shaft 239 and no attention need be given to the die advancing mechanism, unless it becomes necessary, because of the change in the size of blank that 50 is to be rolled, to vary the velocity ratio of the cam 244. This may be done by changing the gears 248 and 249. Although various structural details are shown in Fig. 9, the 55 figure is to a considerable extent diagrammatic. This is true of the arrangement for holding small pinions while they are being rolled. The scale of Fig. 9 is too small to show this, but it is to be understood that 60 the same arrangement may be employed as is illustrated in Fig. 8. The gear 214 is driven at the speed of the motor and for this reason it is desirable to employ a friction clutch at 217. In Fig. 9^A the crank 222 and 65 pitman 223 are shown at dead center; they are at this and the other dead center once in each revolution of the crank and as they approach and leave dead centers the pinion 226 moves very slowly. For this reason a positive instead of a friction clutch may be 70 used at 227, if desired.

Referring now to Fig. 8, the numeral 210 is again used to indicate a pinion on which teeth are being rolled. This pinion is seated in a recess formed in a stout conical block 75 275 that is bolted to a flange formed on the end of a shaft 276. The recess is formed to receive the portion of the blank pinion adjacent to the base of its pitch cone, and it extends outward from the axis of the blank far enough to afford support for all of the metal in the blank which is subjected to direct pressure from the die. For the purpose of clamping the blank in the recess or 80 holder I provide a pull-rod 277 which passes longitudinally through the shaft and may be forced endwise in either direction by a hand wheel 278. The end of the rod is arranged to act as an arbor for the blank and for this purpose is preferably somewhat 85 tapered. Beyond the arbor the rod is threaded to receive a nut 279. When the blank is being placed the rod is projected from the block 275 sufficiently to allow the blank to be pushed firmly on the arbor by 90 the nut 279. The hand wheel 278 is then rotated to draw the blank into the recess in the holder. The bore of the blank is thus quite filled by the arbor and the body of the blank 95 is clamped between the nut and the walls of 100 the recess. In order to gain time and prevent the blank cooling too much before teeth can be rolled on it the nut and the threaded part of the arbor may be mutilated; that is, the threaded part of the arbor may have two 105 or three longitudinal channels cut in it which in the aggregate amount to about one half of the circumference of the rod, and similar channels cut in the nut. The nut can then be slipped on the rod until it is in 110 contact with the blank and the blank then clamped by turning the nut only a fraction of a revolution. This expedient being well known, it is deemed unnecessary to illustrate it. The teeth on the blank are formed with 115 a die roll 280 mounted on the end of a longitudinally movable shaft 281. This shaft is carried by a tubular shaft 282 arranged to rotate in bearings 283 carried by a member 284 corresponding to the superbase in Fig. 120 9. The shafts 281 and 282 are connected by a spline 285 whereby they are made to rotate as a unit. The timing gear 286 is secured to the shaft 282 and meshes with a timing gear 287 secured to the shaft 276; these gears 125 maintain a fixed speed ratio between the blank and die while teeth are being rolled on the blank and it is evidently immaterial

which shaft, 276 or 282, is the driver and which the driven. While the shafts are rotated the shaft 281 is moved longitudinally toward the blank by the mechanism which 5 has been previously described or any other suitable means.

The pressure against the blank while teeth are being rolled upon it is evidently parallel to the axis of the shaft 281. A dotted 10 line 290 parallel to the axis of the shaft 281 and coincident with the inner edge of the annulus constituting the die is seen to be within the confines of the holder on the side opposite to that from which the pressure is 15 imparted. The bulk of the strain is therefore sustained by the block 275 and there is no tendency to deflect the arbor inside of the blank. The arbor performs a useful function in filling the bore of the blank and 20 withstanding the strain tending to move the nut 279 longitudinally away from the holder, but it is relieved of substantially all lateral strain. As the pinion 210 has the smallest 25 number of teeth that approved engineering practice permits to be used, it is seen that Fig. 8 illustrates the most extreme case. Any increase in the number of teeth in the pinion will evidently improve the conditions.

In the machines for rolling bevel gears 30 that I have heretofore disclosed the timing gear and blank holder have been comparatively close together and there has been no journal between them. This is also the case in the machine shown in the present Fig. 1. 35 In Fig. 8 the shaft 276 is supported by a bearing 295 placed between the blank holder 275 and timing gear 287. Another bearing is assumed to be placed between the flanges 296. This arrangement for supporting the 40 shaft 276 is peculiarly appropriate in a machine designed for rolling small pinions, where the pressure may be nearly perpendicular to the axis of the shaft. The bearing 295 is assumed to be bolted to the base of the 45 machine; and in order that the blank holder 275 and timing gear 287 may be readily changed to prepare the machine for rolling gears of various sizes the bearing 295 is split vertically, so that it can be removed 50 without disturbing the shaft 276.

While gears alone have been hereinbefore referred to, it is not to be understood that the field for my machines and the method they carry out is limited to gears. 55 Other rotary articles may be rolled by these machines by simply substituting a die of appropriate design; and there are other articles than gears which it would be advantageous to roll by the method I have described. As an example I may mention 60 sprocket wheels. It is not necessary, even, that the die have teeth or other projections.

It is not to be understood that I consider my invention limited in its practical appli-

cations to the examples shown, as it is clear 65 that various modifications are possible without departure from the spirit of the invention or exceeding the scope of my claims.

What I claim is as follows:

1. In a gear rolling machine, a toothed 70 die, means for rolling a heated blank against said die, first alternately in opposite directions and then continuously in one direction, and means for producing relative movement of approach between the die and 75 blank.

2. In a gear rolling machine, a toothed die, means for rolling a heated blank against said die, first alternately in opposite directions and then continuously in one direction, 80 means for producing relative movement of approach between the die and blank, and means for varying said movement of approach according to any predetermined schedule relative to the velocity of rotation. 85

3. In a gear rolling machine, a toothed die, means for rolling a heated blank against said die, first alternately in opposite directions and then continuously in one direction, and means for producing relative 90 movement of approach between the die and blank during the alternating operating and discontinuing the movement of approach during at least part of the continuous rolling. 95

4. In a gear rolling machine, a toothed die, means for rolling a heated blank against said die, first alternately in opposite directions and then continuously in one direction at a different velocity than during the 100 alternating operation, and means for producing relative movement of approach between the die and blank. 105

5. In a gear rolling machine, a toothed die, means for rolling a heated blank against 110 the die, first alternately in opposite directions at a speed best adapted to displace the metal and form teeth on the blank, and then continuously in one direction at a speed best adapted to finish the surfaces of the teeth, 115 and means for producing relative movement of approach between the die and blank during the tooth forming operation and such part of the finishing operation as is desired. 120

6. In a gear rolling machine, a rotary 115 toothed die, means for rolling a heated gear blank against said die, first alternately in opposite directions at a relatively low velocity and then continuously in one direction at increased velocity. 120

7. In a gear rolling machine, a rotary toothed die, means for rolling said die and a heated blank together alternately in both directions, means for concurrently producing relative movement of approach between the die and blank, whereby to sink the die teeth into the blank and form teeth on the latter, and means for maintaining fixed 125

velocity ratio between the die and blank during the tooth forming operation.

8. In a gear rolling machine, a rotary toothed die, means for rolling said die and a heated blank together alternately in both directions and concurrently producing relative movement of approach whereby the die teeth are sunk into the blank to form teeth thereon, and means for coordinating the rotary motion with said movement of approach, so that one is proportional to the other.

9. In a gear rolling machine, a toothed die, means for rolling a heated gear blank against the die alternately in both directions, rotating the blank approximately from one to three revolutions in each direction, at the same time pressing the teeth of the die into the blank while maintaining fixed velocity ratio between the die and blank, and means for following said alternate rolling by continuous rolling in one direction, rotating the blank thus a comparatively large number of revolutions.

10. In a machine for rolling gears, a gear blank holder, a shaft arranged to rotate in one direction, means driven by said shaft for rotating the holder alternately in both directions, means also driven by said shaft for rotating the holder continuously in one direction, and means whereby one or the other of said means is put into operation.

11. In a machine for rolling gears, a gear blank holder, a shaft arranged to rotate in one direction, means driven by said shaft for rotating the holder alternately in both directions, means also driven by said shaft for rotating the holder continuously in one direction, a manually operable lever whereby one or the other of said means is put into operation.

12. In a machine for rolling gears, a gear blank holder, a shaft arranged to rotate in one direction, means driven by said shaft for rotating the holder alternately in both directions, means also driven by said shaft for rotating the holder continuously in one direction, a manually operable lever whereby one or the other of said means is put into operation and means whereby putting either into operation before operation of the other is suspended is prevented.

13. In a machine for rolling gears, a gear blank holder, a shaft arranged to rotate in one direction at uniform velocity, means operated by said shaft for rotating the holder alternately in both directions, means also operated by said shaft for rotating the holder continuously in one direction at a different velocity than that at which it rotates when oscillating, and means whereby one or the other of said means is put into operation.

14. In a machine for rolling gears, comprising a rotary toothed die, a blank holder,

and timing mechanism whereby the die and holder are compelled to rotate at a fixed velocity ratio: a shaft arranged to rotate in one direction, means driven by said shaft for rotating the die and holder alternately in both directions, means also driven by said shaft for rotating them continuously in one direction, and mechanism for producing relative movement of approach between the die and holder, said mechanism operating in time with the movement of the die and holder, so that the movement of approach is in accordance with the velocity of the die and holder.

15. In a machine for rolling gears, comprising a rotary toothed die, a blank holder, and timing mechanism whereby the die and holder are compelled to rotate at a fixed velocity ratio: a shaft arranged to rotate in one direction, means driven by said shaft for rotating the die and holder alternately in both directions, means also driven by said shaft for rotating them continuously in one direction, and mechanism for producing relative movement of approach between the die and holder, comprising a cam which may be formed so that the movement of approach will have any desired characteristics, the rotation of said cam being timed to that of the die and holder so that the movement of approach is modified in accordance with the velocity of the die and holder.

16. In a machine for rolling gears, comprising a rotary toothed die, a blank holder, and timing mechanism whereby the die and holder are compelled to rotate at a fixed velocity ratio: a shaft arranged to rotate in one direction, means driven by said shaft for rotating the die and holder alternately in both directions, means also driven by said shaft for rotating them continuously in one direction, and mechanism for producing relative movement of approach between the die and holder; said mechanism comprising a shaft which is oscillated or rotated continuously in unison with the die and holder and at proportional velocity, a member that is required to rotate when said shaft rotates, but always forward, and means for so driving said member from said shaft.

17. In a machine for rolling gears, comprising a rotary toothed die, a blank holder, and timing mechanism whereby the die and holder are compelled to rotate at a fixed velocity ratio: a shaft arranged to rotate in one direction, means driven by said shaft for rotating the die and holder alternately in both directions, means also driven by said shaft for rotating them continuously in one direction, and mechanism for producing relative movement of approach between the die and holder; said mechanism comprising a shaft which is oscillated or rotated continuously in unison with the die and holder,

- a cam that is required to rotate forward only and a rectifying mechanism through which the shaft drives the cam.
18. In a gear rolling machine comprising a rotary toothed die, a blank holder and timing mechanism whereby the die and holder are compelled to rotate at a fixed velocity ratio; a jack shaft arranged to rotate the die and holder, a main shaft which rotates only in one direction, means for driving said jack shaft thereby through a clutch; means, also clutch controlled, whereby the main shaft oscillates the jack shaft, and a manually operable lever whereby to actuate the clutches selectively, so that the die and holder may be oscillated, driven continuously in one direction or stopped, at will.
19. In a gear rolling machine comprising a rotary toothed die, a blank holder and timing mechanism whereby the die and holder are compelled to rotate at a fixed velocity ratio; a jack shaft arranged to rotate the die and holder, a main shaft adapted to rotate in one direction, a driving connection, including a clutch, for driving the jack shaft from said main shaft in one direction, mechanism, also clutch controlled, for oscillating the jack shaft, rotating it approximately from one to three revolutions alternately in both directions at substantially lower speed than when it is rotated in one direction only; two separate clutch shifting devices, one to control the oscillatory and the other the continuous drive, a manually operable lever whereby either shifting device may be operated, and means for compelling either clutch to be thrown out before another can be thrown in.
20. In a gear rolling machine comprising a rotary toothed die, a gear blank holder and mechanism whereby the die and holder are made to rotate at invariable velocity ratio; mechanism for producing relative movement of approach between the die and holder, comprising a cam whereby said movement of approach is given the desired characteristics, said cam requiring rotation in one direction only, a member whereby to rotate the die and holder, said member being revolvable either alternately in both directions or continuously in one direction, driving the die and blank accordingly; an automatic clutch whereby said member drives the cam when it rotates in the direction rotated by the cam, and a second automatic clutch and a reversing mechanism whereby said member drives the cam when it rotates in the direction opposite to that rotated by the cam.
21. In a gear rolling machine comprising a rotary toothed die, a gear blank holder and mechanism whereby the die and holder are made to rotate at invariable velocity ratio; mechanism for producing relative movement of approach between the die and holder, comprising a cam whereby said movement of approach is given the desired characteristics, said cam requiring rotation in one direction only, a member whereby to rotate the die and holder, said member being revolvable either alternately in both directions or continuously in one direction, driving the die and blank accordingly; an automatic clutch whereby said member drives the cam when it rotates in the direction rotated by the cam, and a second automatic clutch and a reversing mechanism whereby said member drives the cam when it rotates in the direction opposite to that rotated by the cam.
22. In a gear rolling machine comprising a rotary toothed die, a gear blank holder and mechanism whereby the die and holder are made to rotate at invariable velocity ratio; a jack shaft connected to drive the die and holder, a main shaft, and mechanism whereby said main shaft rotating in one direction rotates the jack shaft alternately in both directions, rotating it approximately from one to three revolutions in each direction repeatedly and concurrently with said relative movement of approach.
23. In a gear rolling machine comprising a rotary toothed die, a gear blank holder and mechanism whereby the die and holder are made to rotate at invariable velocity ratio; a shaft arranged to rotate in one direction, two gears loosely mounted on said shaft, one of which is adapted to drive the die and holder in one direction and the other to drive them in the opposite direction, a clutch whereby to establish a driving connection between each of the gears and said shaft, shifting mechanism for throwing the clutches in and out, a cam shaft driven by the aforesaid shaft, and cams thereon to operate the shifting mechanism and automatically throw the clutches in and out alternately.
24. In a gear rolling machine comprising a rotary toothed die, a gear blank holder and mechanism whereby the die and holder are made to rotate at invariable velocity ratio; two clutches, means for driving the die and blank in one direction when one of these clutches is closed and for driving them in the opposite direction when the other clutch is closed; automatic shifting mechanism for closing said clutches alternately, said mechanism reopening each clutch before closing the other, and means for throwing the shifting mechanism into and out of operation, with provision for opening either clutch that happens to be closed when said mechanism is thrown out of operation.
25. In a machine for rolling gears, a holder for blanks, a die roll, a movable support for the die with power actuated means for moving said support to press the die teeth into a blank in the holder, and a man-

- ually actuated member to move the die support into engagement with the blank, enabling the operator to use the die for locating a partly finished blank in the holder.
26. In a machine for rolling gears, a rotatable blank holder, a die for rolling teeth on bevel gear blanks, said die being carried on the end of a revoluble shaft which is moved longitudinally to press the rotating die into a blank carried by the rotating holder to form teeth thereon, and a manually operable lever whereby the shaft may be moved longitudinally though it is not rotating and the die used for locating a partly finished blank in the holder.
27. In a machine for rolling bevel gears, a holder for supporting a blank, a toothed die adapted to roll teeth on a bevel gear blank carried by the holder, and means for oscillating the die and holder and concurrently producing relative movement of approach therebetween to form teeth on the blank.
28. In a machine for rolling bevel gears, a holder for supporting a blank, a toothed die adapted to roll teeth on a bevel gear blank carried by the holder, means for oscillating the die and holder and concurrently producing relative movement of approach therebetween, and means for maintaining fixed speed ratio between the die and holder.
29. In a machine for rolling bevel gears, a shaft, a blank holder carried by the end of said shaft, a timing gear secured to the shaft at a point removable from the holder, and a bearing between the blank holder and timing gear for supporting the shaft; said blank holder having a recess adapted to receive and afford support for the portion of a bevel gear blank adjacent to the base of its pitch cone.
30. In a machine for rolling bevel gears, a shaft, a blank holder carried by the end of said shaft, a timing gear secured to the shaft at a point removed from the holder, and a bearing between the blank holder and timing gear for supporting the shaft; said blank holder having a recess adapted to receive and afford support for the portion of a bevel gear blank adjacent to the base of its pitch cone; a pull rod arranged to slide longitudinally in the shaft, one end extending through the blank holder and tapered to form an arbor for the blank, a nut to screw on the arbor, whereby to force the blank on the arbor, and means for pull-
- ing the rod endwise in the shaft, thus drawing the blank firmly into the recess.
31. In a machine for rolling teeth, on bevel pinions having comparatively few teeth, a shaft, a blank holder on the end thereof having a recess adapted to receive and afford support for the portion of the pinion adjacent to the base of its pitch cone, said recess having a rim that extends a sufficient distance from the axis of the holder to support all of the metal in the blank that is subject to direct pressure from the die; a tapered arbor longitudinally movable with reference to the holder, a nut on the arbor to draw the blank tight on the arbor, and means for drawing in the arbor so as to clamp the blank in the recess.
32. In a gear rolling machine, a die roll, a blank holder, a timing gear connected to said holder, a journal bearing between the timing gear and holder, and means for producing relative movement of approach between the die roll and blank holder whereby to sink the die teeth into a blank in the holder and form teeth thereon, said movement of approach being rectilineal and at an angle to the axis of the blank less than 90%.
33. In a gear rolling machine, a die roll adapted to roll teeth on bevel gears, a blank holder adapted to support bevel gear blanks, a timing gear connected to the holder, a journal bearing between the blank holder and said gear, and means for producing relative movement of approach between the die and holder, whereby to roll teeth on blank carried by the latter.
34. In a metal rolling machine, a die, means for rolling a heated blank against the die, first alternately in opposite directions and then continuously in one direction, and means for producing relative movement of approach between the die and blank.
35. In a metal rolling machine, a die, means for rolling a heated rotary blank against the die, first alternately in opposite directions and then continuously in one direction, and means for producing relative movement of approach between the die and blank.
